UNITED STATES PATENT OFFICE.

EDWIN A. ISAKSON, OF MCKEESPORT, PENNSYLVANIA.

PISTON PACKING.

Application filed June 12, 1923. Serial No. 644,875.

To all whom it may concern:

Be it known that I, EDWIN A. ISAKSON, a citizen of the United States, and resident of McKeesport, in the county of Allegheny and State of Pennsylvania, have invented certain new and useful Improvements in Piston Packings, of which the following is a specification.

This invention relates to piston head packings and while not limited thereto relates more particularly to piston head packings especially adapted for use on the pistons of hydraulic cylinders or the like where they will be subjected to the action of moisture.

One object of this invention is to provide a packing for the pistons of hydraulic cylinders which will become tighter when subjected to moisture, thus forming a perfect seal between the piston and cylinder walls.

Another object of this invention is to provide a packing that will have a materially longer life than the packings heretofore used in hydraulic cylinders.

A further object is to provide an improved packing composed of a metal cup and fiber ring such as described in the following specification and illustrated in the accompanying drawings.

In the drawings, Figure 1 is a longitudinal sectional elevation through a hydraulic cylinder and piston having my invention applied thereto.

Figure 2 is a sectional elevation through one of the packing rings.

Referring more particularly to the drawings, the numeral 2 designates the barrel or body portion of the cylinder which has a removable head 3. The usual piston, comprising a rod 4, head 5, follower ring 6, and choker 7, is mounted in the cylinder body 3. The follower ring 6 is secured to the piston head 5 by stud bolts 8 and the choker 7 is provided with a screw threaded stem 9 which is threaded into the piston head.

The rear end of the piston head 5 is provided with the usual enlargement or rim 10 forming a shoulder 11 against which a lower spacing ring 12 abuts. The lower spacing ring 12 is cut away to form a shoulder portion 14, which abuts against the shoulder 11 of the piston head, and a flange portion 15 which overlies the rim 10.

A forward spacing ring 16 and intermediate spacing ring 17 are mounted on the piston head 5 and spaced away from each

other and the rear ring 12 so as to form annular recesses 18 for the reception of packing rings, two of which are mounted in each of the recesses. The spacing rings 60 are formed from a suitable anti-friction metal such as brass, and are constructed to form a relatively tight fit between the piston head 5 and cylinder body 2.

Each of the packing rings comprise a 65 metal cup 20 composed of copper or other non-resilient soft metal and comprise an outer band portion 21 and an inwardly directed flange 22. The edge of the band portion 21 opposite the flange 22 is beveled as 70 at 23 so as to permit the pressure within the cylinder to enter and aid in expanding the band portion against the cylinder wall. The metal cups in the lower annular recess have their beveled edges directed downwardly, 75 while the cups in the upper recess have their beveled edges directed upwardly.

A hard red fiber ring 24 is fitted snugly within each of the metal cups. The hard red fiber is characterized by being expandable 80 when moistened and this quality is utilized in the functioning of the present packing rings. When the hydraulic cylinder is operated the fiber rings 24 will become wet and immediately expand or swell, and 85 since the rings 24 are confined between the soft metal cups and the hard metal piston head, the force of expansion will be exerted on the soft metal cups and force the band portion 21 thereof outwardly into close contact with the cylinder wall, thus forming 90 a good seal.

Heretofore, leather, asbestos and other soft materials have been used for packing the pistons of hydraulic cylinders, but due to 95 wear it is necessary to replace such packings about every two or three days when the cylinder is using high pressure continually. While experience has shown that the present packing rings composed of copper cups 100 and red fiber rings will make a better seal and will last about six weeks before they are worn sufficiently to need replacement.

It will thus be seen that the savings for each high pressure hydraulic cylinder 105 packed in accordance with this invention, will amount to thousands of dollars each year, and the operation of the cylinder will be materially improved, due to the seal between the piston and cylinder wall being 110 better than the old forms of soft packing.

While I have described my invention as

particularly adapted for use with hydraulic cylinders, it will be understood that I do not wish to be limited to such use since it may be used in other cylinders without departing from the scope of my invention as defined in the appended claims.

I claim:—

1. The combination with a piston having a plurality of spacing rings thereon spaced 10 to form at least one annular recess, of at least one packing ring mounted in said recess, said ring being composed of a non-elastic soft metal cup, and a hard fiber ring mounted within said cup, said ring being characterized by being expansible when moistened and being adapted when moistened to force said metal cup outwardly into contact with the cylinder wall.
2. The combination with a piston, of at least one packing ring comprising a non-elastic soft metal cup, and a hard fiber ring within said cup, said fiber ring being characterized by being expansible when moistened and being adapted when moistened to expand said cup.
3. A packing ring for pistons of hydraulic cylinders, comprising a non-elastic soft metal cup, and a hard fiber ring within said cup, said fiber ring being characterized by being expansible when moistened and being adapted when moistened to expand said cup.
4. A packing ring for pistons of hydraulic cylinders, comprising a copper cup, and a hard red fiber ring mounted within said cup, said fiber ring being characterized by being expansible when moistened and being adapted when moistened to expand said cup.
5. The combination with a piston having 40 a plurality of anti-friction metal spacing

rings thereon spaced to form a plurality of annular recesses, of at least one packing ring mounted in each of said recesses, said rings comprising a non-elastic soft metal cup, and a hard fiber ring mounted within said cup, said ring being characterized by being expansible when moistened and being adapted when moistened to form said metal cup outwardly into contact with the cylinder wall.

6. The combination with a piston for a hydraulic cylinder having a plurality of anti-friction metal spacing rings thereon and spaced to form a pair of annular recesses, of a pair of packing rings mounted 55 in each of said recesses, each of said packing rings comprising a copper cup, and a rigid non-resilient fiber ring mounted within said cup, said ring being characterized by being expansible when moistened and 60 being adapted when moistened to force said metal cup outwardly into contact with the cylinder wall.

7. The combination with a piston for a hydraulic cylinder having a plurality of 65 anti-friction metal spacing rings removably mounted thereon and spaced to form a pair of annular recesses, of a pair of packing rings mounted in each of said recesses, each of said packing rings comprising 70 a non-resilient soft metal cup, and a rigid non-resilient fiber ring mounted within said cup, said ring being characterized by being expansible when moistened and being adapted when moistened to force said metal 75 cup outwardly into contact with the cylinder wall.

In testimony whereof I have hereunto set my hand.

EDWIN A. ISAKSON.
